W. S. BARKER

COAL GAS AND OXYGEN BURNER

Filed Feb. 16, 1928

Inventor:

William S. Barker;

By

Robert W. Randle,

Attorney.

UNITED STATES PATENT OFFICE.

WILLIAM S. BARKER, OF KNIGHTSTOWN, INDIANA.

COAL-GAS AND OXYGEN BURNER.

Application filed February 16, 1928 Serial No. 254,847.

The object of my present invention, broadly stated, is to provide a construction consisting of an attachment for furnaces, or other heating plants, particularly coal-burning furnaces or the like, to provide a hot-blast for producing proper combustion of the fuel and of the gases emanating therefrom whereby every unit of the product of combustion will be utilized in the production of usable heat, and at the same time eliminating the production of smoke and soot, and the escape of unburned gas, and also requiring less fuel for producing a given amount of heat and by which the residue or ash will be reduced to a minimum, thereby reducing the cost of maintenance and the reduction of the labor of attention.

Other objects are to provide an attachment, for the purposes above mentioned, which is simple in character, strong and durable in construction, not subject to deterioration, involving no relatively moving parts after being adjusted, easily installed without damage to or previous preparation of the furnace therefor, which can be installed at a minimum of expense and which can be manufactured and sold at a comparatively low price.

Other particular objects and advantages will suggest themselves in the course of the following description.

The preferred means for carrying out the principles of my invention in a practical manner is shown in the accompanying drawings, in which—Figure 1 is an outside or front elevation showing a furnace door and the outer end portion of my attachment in operative position in connection therewith. Figure 2 is a central longitudinal vertical section as taken through my device and the door with which it is connected, as taken on the line 2—2 of Fig. 1. Figure 3 is a side elevation of the invention, showing certain parts of the device turned at an angle from that of Fig. 2. Figure 4 is an end view of the discharge end of the nozzle. And Figure 5 is a cross section of the outer end of the outer fitting, as taken on the line 5—5 of Fig. 2.

Similar indices denote like parts throughout the several views.

In order that the construction, the operation, and the several advantages of my invention may be more fully understood and appreciated, I will now take up a detailed description thereof, in which I will set forth the same as comprehensively as I may.

In the drawings letter A denotes a furnace door which, in this instance, has a plurality of slot openings B formed therethrough, which are usually controlled by a sliding damper, not shown.

The invention includes a pan-shaped, oblong, member forming an air reservoir, and it consists of a flat wall, or bottom, 1 having integral therewith a flange 2 extending outward at an angle and entirely surrounding the edge of the wall 1. The edge of the flange 2 is adapted to contact against the inner side of the door A, whereby all of the slots B will be covered thereby and which, together with the inner face of the door, forms a chamber 3, with all of the openings B leading thereto from the outside. In the center of the wall 1 a comparatively large aperture is provided, around which a collar 4 is formed integral with the wall 1, and extending inward therefrom.

Numerals 5 denotes the first right-angular, or L-shaped, fitting which is of the same diameter throughout and without flanges or threads on either of its ends. The longer end portion of the fitting 5 is adapted to slide snugly into said collar 4 and the wall 1. A chine or ridge 6 is formed around circumferentially on and near the center of the longer portion of the fitting 5, to engage the inner end of the collar 4, whereby the fitting 5 is prevented from contacting with the door A when the fitting 5 is placed in said collar 4. Four equally divided apertures 7 are formed through the wall of the outer end portion of the fitting 5, for the purpose hereinafter made apparent. Two hook-bolts, 8 and 9, are provided, each having a hook, 10 and 11 respectively, formed by their inner end-portions, with their outer portions threaded, and provided with the respective nuts 12 and 13. Near the juncture of the hooks with the body of their respective bolts, a lug, 14 and 15, respectively, is formed, for the purpose herein-after set forth.

The exterior bracket comprises a circular ring or washer 16, which is adapted to contact with the outer side of the door A. Numerals 17 and 18 denote standards which extend outward substantially parallel with each other from the ring 16, with which they are integral, and from opposite points of the aperture formed through said ring. The upper ends of said standards are connected integrally by the cross-bar 19. Said cross-bar 110

has two, spaced apart, slotted apertures, *a* and *b*, formed therethrough in which said bolts 8 and 9 may freely operate as desired.

In order to assemble the parts above mentioned one has first to bring the air-box or pan-shaped member to position against the inner face of the door A. The fitting 5 is then inserted to the position in which it is shown in Figs. 2 and 3. The hook portions of the bolts 8 and 9 are then inserted through slots B of the door and the hooks 10 and 11 are then engaged into two of the oppositely disposed apertures 7, as in Fig. 3, with the bolts extending outward through slots B. The said bracket is then placed against the outer face of the door A, with the aperture in the ring 16 concentric with the inserted end of the fitting 5. While bringing said bracket to position, the outer ends of the bolts are entered through the respective apertures, *a* and *b*, in the cross-bar 19. The next operation is to run the nuts 12 and 13 onto the projecting end portion of the bolts 8 and 9. Now by simply tightening said nuts against the cross-bar 19 it is evident that all of said parts will be securely clamped into rigid position in connection with the door A, as the chine 6 will contact with the inner end of the collar 4, whereby preventing the member 5 from being drawn outward.

The next element employed in this construction is the U-shaped fitting 20, one of its ends terminating in a flange 21 which is adapted to receive therein the upturned end 35 of the fitting 5, where it may be locked by means of the set-screw 22, or otherwise.

The next element in the construction is the L-shaped fitting 23, which may be termed the nozzle member, and its upturned shorter portion terminates in a collar 24, which is adapted to receive the outer down-turned end of the member 20, where it is secured by the set-screw 25. The projecting or inner end of the fitting 23 terminates in a rounded or hemispherical nozzle portion 26, which is cut by two slots, *c*, and *d*, crosswise of each other, as in Fig. 4.

The members 5, 20 and 23 are all tubular, and they are made adjustable in order that they may be arranged to meet various conditions, as for instance the member 5 may be turned from the position shown by simply changing the hooks 10 and 11 to the other pair of apertures 7; by loosening the set-screw 22 the member 20, carrying with it the member 23, to any angle desired; and likewise by loosening the set-screw 25 the member 23 may be swung to any angle desired; or a combination of said adjustments may be made.

60 The arrangement of my device is such that the main portions thereof are located inside the combustion chamber of the furnace, with the nozzle above and directed into or toward the center of the fire and therefore all parts 65 thereof will become very hot. Then if all

of the air inlets be closed the suction from the chimney will draw the air in through the slots B into the chamber 3, where it will be highly heated and will then pass through the fittings, 5, 20 and 23, and will finally be ejected through the nozzle in a super-heated condition. As it passes through the slots *c* and *d* it will be broken up and will be distributed over the bed of fuel in the furnace and will be driven into the gases arising from the fuel, which will cause the gases to burn before they can pass away, for the reason that they will be supplied with the proper amount of super-heated oxygen which will cause them to burn with great intensity and deliver the maximum of heating units. By reason of the above every unit of heat in the fuel will be converted into usable heat and thereby accomplishing the objects of my invention in a simple, practical, scientific, and highly efficient manner.

It is to be understood that my device is not to be limited to a furnace door or even to a furnace, in the common acceptation of that term, as it may be employed with any kind of wall or partition. Neither is it limited to the slots B, as shown, as it may be used with a single round or other shaped aperture in the door or partition. Neither is the device to be limited to the use of set-screws for retaining the fittings in adjusted position, as other means may be employed for that purpose. And in place of the outside bracket I have shown it is evident that a hemispherical disk and a single bolt may be employed in place thereof.

I desire that it be understood that various other changes may be made in the various details of construction from that shown without departing from the spirit of the invention and without sacrificing any of the advantages thereof which are new and useful.

Having now fully shown and described my invention, what I claim, and desire to secure by Letters Patent of the United States, is—

1. An attachment for the purpose set forth comprising, in combination with a partition having an aperture therethrough, an air chamber contacting with the inner face of said partition with said aperture opening thereto, an L-shaped fitting having one end thereof located in said air chamber with its other end located inward therefrom, an L-shaped nozzle-fitting spaced from and in alignment with said first fitting, a U-shaped fitting connecting the two L-shaped fittings, and an air distributing nozzle formed on the discharge end of said nozzle-fitting, substantially as set forth.

2. In combination with a door having apertures formed therethrough, a coal-gas and oxygen burner mounted to said door and comprising, an air reservoir forming member contacting with the inner face of the door with said aperture opening thereto,

an L-shaped fitting leading from the interior of said reservoir forming member, means for clamping all of said members to the door without forming apertures therefor in the door, a U-shaped fitting adjustably attached to said L-shaped fitting, a second L-shaped fitting also adjustably attached to the U-shaped fitting, and an air distributing nozzle formed on the free end of the second L-shaped fitting.

3. A coal-gas and oxygen burner comprising-

ing an air reservoir, a tubular L-shaped fitting leading from said reservoir, a U-shaped tubular fitting adjustably connected with said L-shaped fitting, a second L-shaped fitting adjustably connected with said U-shaped fitting, a nozzle formed on the free end of the second L-shaped fitting, and means for detachably connecting said parts in operative position. 15

WILLIAM S. BARKER.
